UNITED STATES PATENT OFFICE.

GARFIELD A. WOOD, OF DETROIT, MICHIGAN.

HOISTING MECHANISM FOR MOTOR-VEHICLES.

1,271,977.

Specification of Letters Patent.

Patented July 9, 1918.

Original application filed August 28, 1916. Serial No. 117,236. Divided and this application filed June 7, 1917, Serial No. 173,377. Renewed April 26, 1918. Serial No. 231,024.

To all whom it may concern:

Be it known that I, GARFIELD A. WOOD, a citizen of the United States, and residing at Detroit, in the county of Wayne and State of Michigan, have invented a new and Improved Hoisting Mechanism for Motor-Vehicles, of which the following is a specification.

It is common practice to dump the contents of truck bodies by lifting the front end upwardly about pivots at the rear end of the chassis, and hydraulic hoisting means has been used for this purpose. The most convenient source from which to operate the hoisting means is the propeller shaft (ordinarily arranged longitudinally of the vehicle); but, on account of the fact that the heavy loads and shocks incident to hoisting are borne on the side frames and independently of the propeller shaft, the deflection of the former is not transmitted to the latter. Again, it is desirable to provide for slight inaccuracies in the construction of either hoisting means or chassis (often made by different manufacturers), whereby assembling of the parts is facilitated. It is further desirable to avoid the liability of leakage which results from independently supporting the pumping and hoisting elements of which the hoisting means as a whole is made up, and to provide for convenient control of the mechanism by the driver of the vehicle. With these ends in view, the present invention consists in a driven shaft of a motor vehicle together with a hollow pump gear through which said shaft passes together with means for driving said pump-gear from said shaft regardless of a possible lack of exact relative alinement of the parts; in a pump mounted on the lower side of the base of the cylinder whereby the body is tilted; in a pump having a valve, both pump and valve being located below the base of the hoisting cylinder, together with a control lever for the valve mounted at a point near the upper end of the cylinder; in a supplementary frame including a plurality of spaced bars extending across between the side bars of the vehicle and having the base of the cylinder resting thereon, and a pump suspended from the base of the cylinder in the space between the spaced bars; and in certain details of construction shown, described and claimed.

The present application is a division of 55 my application for patent Serial No. 117,236, filed August 28, 1916.

In the drawings,

Figure 1 is a fragmentary side view of a motor truck showing a preferred embodiment of my invention. Fig. 2 is a part front elevation and part section on the line 2-2 of Fig. 1, parts being omitted. Fig. 3 is a part-elevation part-central vertical section corresponding to Fig. 1. Fig. 4 is an 65 enlarged view on the line 4-4 of Fig. 3. Fig. 5 is a section on the line 5-5 of Fig. 3. Fig. 6 is a plan view of the clutch mechanism, parts being broken away. Fig. 7 is a section on the line 7-7 of Fig. 6. 70

Similar reference characters refer to like parts throughout the several views.

1 indicates the side frames of the vehicle to the rear end of which are secured brackets 2 bearing pivots 3 about which the body 4 75 may be swung vertically for dumping purposes. The body may include the longitudinal frame pieces 5 so arranged as to rest, when in lowered position, either on the side frames 1 or on special chairs carried thereby (not shown). This general construction is well known.

The side frames may be cut away at a point 6 forward of the front end of the body, and may there support the cross bars 85 8 (preferably angle-irons having their horizontal flanges facing each other) upon which rests the flanged base 9 of a hoisting cylinder 10, the piston rod 11 of which, through cross bar 12, sheaves 13, cables 14 (shown 90 in dashed lines in Fig. 1), equalizing bar 15, shackle 16 (omitted in Fig. 1) and brackets 17 secured to the body, serves to elevate the front end of the latter. The cylinder has secured to its upper end a chamber or tank 19 that may be in free communication with the interior of the cylinder above the piston, whereby storage space for liquid is formed.

Attached to the base 9 by bolts 21 is a 100 gear pump 22 containing the driven gear 23 and the annular driving gear 24, the latter being keyed on a sleeve 25 rotatable in roller bearings 26 that turn in the threaded hubs 28 integral with the pump casing. The 105 joints between the hubs and the sleeve may be sealed by the packing 29 and packing nuts 30, and in order to allow the rollers to

- be assembled, a retaining ring 31 may be threaded into each of the hubs. Passing through the sleeve is the usual propeller shaft 34, and it will be seen that the relative dimensions of the parts is such as to allow considerable deflection of the side frames and hoisting cylinder without bringing the sleeve into bearing engagement with the shaft.
10. The latter has rigidly secured thereto a clutch member that may be formed of the duplicate clamp sections 35 secured together by bolts 36. Slidably mounted upon the sleeve is a clutch shifting member 38, grooved at 39 to receive the yoke blocks 40 into which are threaded the bolts 41 that also pass through the ends of the levers 42. The latter are secured to a shaft 43 that is mounted in the ears 44, rigid with the pump casing, and may be swung about the axis of the shaft by an arm 45 and a link 46 pivoted at 47 to a lever 48 that, in turn, is pivoted to the tank 19 at 49. Projecting from the member 38 at each side is an ear 50 (Fig. 6) through which passes a bolt 51 that is threaded therein; reduced portions of these bolts also extend through an annular clutch ring 52 and have reduced inner ends 53 that slide longitudinally in slots 54 formed in the sleeve 25. Thus the sleeve, the member 38 and the clutch ring are constrained to rotate together, while the two last mentioned members are slidable on the sleeve. The clutch ring is slidable radially of the propeller shaft on the pins or bolts 51 to automatically compensate in one direction for lack of alinement between the propeller shaft and the sleeve. Lack of alinement in a direction at right angles to that first mentioned is provided for by slippage of the clutch members 35 on teeth 55 that project from the ring 52, and overlap the members 35 when thrust to the left (Fig. 6). Consequently, rotation of the shaft may be transmitted undiminished to the sleeve even though their axes are not coincident and regardless of the fact that considerable deflection of the sleeve may take place when lifting heavy loads.
50. As stated previously, the tank 19 constitutes a storage receptacle for liquid (preferably oil) and communication is established between the tank and intake passage 58 of the pump (Fig. 5) by a pipe 59 and fitting 60, and is expelled from the gears through the discharge passage 60' that may be brought into connection with the space between the lower end of the cylinder and the piston (not shown) by a three-way valve 61 and passage 62 (Fig. 5). Another passage 63 leads from the intake to the passage 62, and, when the valve is in the position shown, the liquid by-passes the gears and the piston sinks. Various other arrangements of passages for the liquid may,

of course, be used, but that described is preferred since, besides the advantages already stated, the liquid may be circulated continuously within the pump itself by turning the valve so as to close the passage 62, 70 which avoids stopping of the engine. The valve may be operated by means of the lever 64, link 65 and lever 66, and the throw of both the lever 66 and the lever 48 may be limited by the stop 67 that projects from 75 the tank 19.

It will be observed that the bars 8 constitute a frame (supplementary to that of the chassis and resting thereon) on which is directly carried a unit which comprises both 80 the hoisting cylinder and the gear pump. This construction is of much importance for the reason that, were the gear pump mounted directly on the chassis or on the engine, the heavy shocks and loads to which 85 the cylinder is subjected and the extremely high liquid pressures which are necessarily employed would cause relative deflections such as would render it practically impossible to maintain tight joints. Again, the 90 construction, being itself assembled and including all necessary parts, is readily assembled on and accommodates itself without alteration to slight variations in the chassis. Its control levers are located at a 95 point where they are accessible to the driver and yet do not interfere with the other control mechanism by which the adjacent foot space is ordinarily substantially filled.

Obviously, the details of the various 100 parts may be changed without departing from the spirit of my invention, I do not, therefore, wish to be limited otherwise than as indicated by the subjoined claims.

I claim:

1. In combination with the frame and a rotatable shaft of a motor vehicle, a hoisting device supported by the frame, and mechanism for actuating the hoisting device from the shaft, said mechanism including a 110 gear pump comprising a housing, a driven gear and a driving gear therein, a hollow rotatable sleeve to which said driving gear is secured, anti-friction bearings in the housing for said sleeve, means for sealing 115 the joints between said sleeve and the housing, said shaft passing through the sleeve and being spaced therefrom, a clutch member secured to the shaft, a second clutch member carried by the sleeve and rotatable 120 therewith, and means for moving said second clutch member longitudinally of the shaft to connect it to or disengage it from the first mentioned clutch member at will, the second clutch member also being spaced 125 from the shaft, whereby deflection of the frame and gear pump, due to loads on the hoisting device, may take place without inducing bending stresses in the shaft.
2. In combination with the frame and a 130

rotatable shaft of a motor vehicle, a hoisting device supported by the frame, and mechanism for actuating said hoisting device, said mechanism including a gear pump comprising a housing, a driving pump gear and a driven pump gear in said housing, a hollow sleeve rotatable in said housing, said driving gear being secured to said sleeve, means for sealing the joints between the 10 housing and the sleeve, said shaft passing through said sleeve and being spaced therefrom, and means for connecting said shaft to said sleeve so that the latter is driven by the former, said means allowing deflection 15 of the frame and pump relatively to the shaft, due to loads on the hoisting device, without inducing transverse bending stresses in the shaft.

3. In combination with the main frame 20 and driving shaft of a motor vehicle, a cross frame supported on the main frame, a pump supported on the cross frame, a hoisting cylinder and piston also supported on the cross frame, means whereby liquid pumped 25 by the pump may cause the piston to be elevated in the cylinder, said pump including a rotatable pumping member spaced from the driving shaft, the driving shaft passing through the pumping member, and 30 means for connecting said driving shaft to said rotatable pumping member so that the latter is driven by the former, said means allowing deflection of the frame and pump, relatively to the shaft, due to loads on the 35 hoisting system, without inducing transverse bending stresses in the shaft.

4. In combination with the frame and a rotatable shaft of a motor vehicle, a hoisting device supported by the frame, and 40 mechanism for actuating the hoisting device from the shaft, said mechanism including a gear pump carried by the frame comprising a driven gear and a driving gear, a hollow rotatable sleeve to which the driving gear is 45 secured, said shaft passing through said sleeve and being spaced therefrom, a clutch member secured to the shaft, a second clutch member carried by the sleeve and rotatable therewith, and means for moving said second clutch member longitudinally of the 50 shaft to connect it to or disengage it from the first mentioned clutch member at will, the second clutch member also being spaced from the shaft, whereby deflection of the 55 frame and gear pump, due to loads on the hoisting device, may take place without inducing bending stresses in the shaft.

5. In combination with the frame and a rotatable shaft of a motor vehicle, a hoisting device supported by the frame, said mechanism including a hollow fluid impelling member, said shaft passing through said hollow member and being spaced therefrom whereby relative movement of the hollow 65 member and the shaft transversely of the

axis of the latter is allowed, and means for driving the hollow member from the shaft at will.

6. In combination with the frame and a rotatable shaft of a motor vehicle, a hoisting device supported by the frame, said device including a liquid impelling member surrounding said shaft and spaced therefrom, and mechanism for actuating the hoisting device from the shaft, part of said mechanism being carried by the shaft and another part being supported independently thereof, one of the parts being capable of movement transversely of the shaft, whereby deflection of the frame in respect to the shaft 70 may take place without inducing bending stresses in the shaft.

7. In combination with the frame and a rotatable shaft of a motor vehicle, a hoisting device supported by the frame, said device including a liquid impelling member substantially concentric with and spaced from the shaft, and clutch mechanism for actuating the liquid impelling member from the shaft, part of said clutch mechanism being carried by the shaft and another part being supported independently thereof, one of the parts being capable of movement 85 transversely of the shaft.

8. In combination with the frame and a rotatable shaft of a motor vehicle, a hoisting device supported by the frame, said device including a liquid impelling member substantially concentric with and spaced from the shaft, and clutch mechanism for 90 actuating the liquid impelling member from the shaft, part of the clutch mechanism being carried by the shaft and another part being supported independently thereof, one of the parts being capable of movement transversely of the shaft, whereby deflection of the frame in respect to the shaft, due to 95 loads on the hoisting device, may take place without inducing transverse bending stresses in the shaft, one of the clutch parts being 100 movable longitudinally of the shaft to engage with or disengage from the other part whereby rotative movement of the shaft is made to cause rotative movement of the 105 clutch part that is supported independently 110 of the shaft.

9. In combination with the frame and a rotatable shaft of a motor vehicle, a hoisting device supported by the frame, said device including a hollow rotatable member 120 supported by the frame and through which the shaft passes, said shaft being spaced from the member, a clutch member secured to the shaft, a second clutch member extending around the hollow rotatable member, one of the clutch members being movable 125 longitudinally of the shaft to be engaged with or disengaged from the other clutch member at will.

10. In combination with the frame and a 130

- rotatable shaft of a motor vehicle, a driven mechanism supported by the frame, said mechanism including a hollow rotatable member supported by the frame and through which the shaft passes, said shaft being spaced from the member, a member surrounding said rotatable member and constrained to rotate therewith and slidable longitudinally thereon, a clutch member supported by said last named member, and a second clutch member supported by the shaft and coöperating with the first clutch member.
11. In combination with the frame and a rotatable shaft of a motor vehicle, a driven mechanism supported by the frame, said mechanism including a hollow rotatable member supported by the frame and through which the shaft passes, said shaft being spaced from the member, a member surrounding said rotatable member and constrained to rotate therewith and slidable longitudinally thereon, a clutch member supported by said last named member, and a second clutch member supported by the shaft and coöperating with the first clutch member, said first named clutch member being tilttable on the slidable member.
12. In combination with the frame and a rotatable shaft of a motor vehicle, a liquid impelling member concentric with said shaft, a sleeve interposed between said member and shaft and rigid with said member, said sleeve being spaced from the shaft and projecting along said shaft in one direction beyond the corresponding end of the member, a bearing for the projecting portion of the sleeve, and clutch means for driving the sleeve from the shaft, said clutch means including two members, one of the members being supported by the projecting portion of the sleeve, the other being carried by the shaft.
13. In combination with the frame and a rotatable shaft of a motor vehicle, a liquid impelling member concentric with said shaft, a sleeve interposed between said member and shaft and rigid with said member, said sleeve being spaced from the shaft and projecting along said shaft in one direction beyond the corresponding end of the member, a bearing for the projecting portion of the sleeve, and clutch means for driving the sleeve from the shaft, said clutch means including two members, one of the members being supported by the projecting portion of the sleeve, the other being carried by the shaft.
14. In combination with the frame and a rotatable shaft of a motor vehicle, a hoisting device supported by the frame, said mechanism including a hollow fluid impelling member, said shaft passing through said hollow member and being spaced therefrom whereby relative movement of the hollow member and the shaft transversely of the axis of the latter is allowed, means for driving the hollow member from the shaft at will, and mechanism for controlling said driving means at will, said mechanism being so constructed and arranged that its weight tends to hold the driving means out of driving relation.

GARFIELD A. WOOD.
